UNITED STATES PATENT OFFICE.

LEONARD MEYRICK MEYRICK-JONES, OF EAST DEREHAM, ENGLAND.

MOTOR ATTACHMENT FOR CYCLES.

SPECIFICATION forming part of Letters Patent No. 709,549, dated September 23, 1902.

Application filed September 20, 1901. Serial No. 75,777. (No model.)

To all whom it may concern:

Be it known that I, LEONARD MEYRICK MEYRICK-JONES, engineer, a subject of the King of Great Britain, residing at Bawdeswell, East Dereham, in the county of Norfolk, England, have invented a certain new and useful Improved Means and Appliance for Enabling Motors to be Used with Bicycles and the Like, of which the following is a specification.

10 This invention has for its object the application of motors to bicycles and the like. This is effected by carrying the motor on a light frame which can be slid backward or forward along and be secured at any desired point to longitudinal slide-bars which are secured by clamps to the cycle-frame, or these bars might be movable backward or forward through the clamps or both together. The frame carrying the motor may be placed 20 between two bicycles which are side by side and at a distance apart from one another. The motor may be mounted on a single transverse bar having clamps at its ends to embrace longitudinal guide-bars, the ends of 25 which are in turn held in clamps on short rods which by other clamps are secured to suitable members of the cycle-frames, the clamps at each end of this attachment being capable of turning to any required angle relatively to each other. Other stay-bars are similarly carried from the motor to the opposite ends of the cycle-frames or as otherwise required. The motor may be arranged to 30 drive a transverse shaft, and pinions on the ends of this shaft may be made to gear with toothed wheels secured to the crank-axle or driving-wheels (either front wheel or back wheel) of the cycles.

35 It is not necessary that the two bicycles should be of the same size or construction. In these respects there may be considerable difference between them. Where required, the steering-gear of the two cycles may be coupled.

40 In place of the motor being carried by a single transverse bar a light open-trussed frame with clamps at its ends might be substituted for the bar.

45 Figure 1 is a side elevation, Fig. 2 a rear elevation, and Fig. 3 a plan, showing two bi-

cycles connected together by a frame made according to my invention and carrying a motor which drives a shaft at the rear of the frame through a belt. Figs. 4, 5, and 6 are similar views of a modified form of frame in 55 which the motor is at the rear. Fig. 7 is a view showing to a larger scale one of the clamps for securing the frame to the bicycles.

In Figs. 1, 2, and 3, *a a* are two bicycles, to whose heads and backstays four rods *b* are 60 secured by clamps *b'*. Each rod carries a clamp *b*², which can be turned at any angle to the clamps *b'* at the other end of its rod. This can conveniently be effected by connecting the clamps *b*² to the rods *b* by a screw- 65 thread of fine pitch, as shown in Fig. 7.

The clamps *b*² hold two longitudinal bars *c*, each carrying a forward socket *c'* and a rear socket *c*². The forward sockets *c'* carry a motor *d*, which may be of any convenient 70 pattern, while the rear sockets carry a transverse bar *e*, provided with bearings *e'* for a shaft *f* driven from the motor by a belt *d'* and having at its ends pinions *f'* gearing with special pinions *a'*, provision being made 75 for enabling the pinions *f'* to run at different speeds for turning corners, on the hubs of the back wheels of the bicycles *a*. The bearings *e'* may be further supported by rods *e*², fixed to the motor-casing. 80

In the modification shown in Figs. 4, 5, and 6 the motor-frame instead of being fixed in sockets fast with the longitudinal bars *c* is carried by clamps *c*³, so that it can be slid along the bars. The motor *d* also is at the 85 rear of the frame and drives the shaft *f* by toothed gearing *f*², while the motion of the shaft *f* is transmitted by belts or straps *f*³ to pulleys *f*⁴ on the back wheels. *g* is a cross-tie connected by rods *g'* to the motor-casing. 90

What I claim is—

1. The combination of two bicycles, a set of clamps engaging their frames, a second set of clamps adjustably carried by the first set, and a motor-frame carried by the second set 95 of clamps.

2. In a motor attachment for cycles, the combination of a set of clamps engaging the bicycle-frames, a second set of clamps adjustably carried by the first set, longitudinal bars 100

50 elevation, and Fig. 3 a plan, showing two bi-

carried by the second set, a motor carried by the longitudinal bars, and means for driving the bicycle-wheels from the motor.

3. In a motor attachment for cycles, the combination of a set of clamps engaging the bicycle-frames, a second set of clamps adjustably carried by the first set, longitudinal bars carried by the second set, a motor carried by

the longitudinal bars, a shaft driven by the motor, and pinions on the shaft engaging to pinions on the hubs of the bicycle-wheels.

LEONARD MEYRICK MEYRICK-JONES.
